DESIGN FOR A CASING FOR LIQUID DISPENSING APPARATUS

Warren H. De Lancey, Springfield, Mass., assignor
to Gilbert & Barker Manufacturing Company,
Springfield, Mass., a corporation of Massa-
chusetts

Application March 10, 1934, Serial No. 51,003

Term of patent 14 years

To all whom it may concern:

Be it known that I, WARREN H. DE LANCEY, a citizen of the United States, residing at Springfield, in the county of Hampden, and State of Massachusetts, have invented a new, original, and ornamental Design for a Casing for Liquid Dispensing Apparatus, of which the following is a specification, reference being had to the accompanying drawing, forming part thereof.

Fig. 1 is a perspective view of a casing for liquid dispensing apparatus embodying the new design; and

Fig. 2 is a sectional plan view taken through the lower part of the casing.

I claim:

The ornamental design for a casing for liquid dispensing apparatus as shown.

WARREN H. DE LANCEY.
